(57) **CLAIM**

The ornamental design for a biometer body as shown and described.

DESCRIPTION

FIG. 1 is a perspective view of a biometer body showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a perspective view showing the biometer body in a state of use.

The broken lines shown in FIG. 9 depict portions of the biometer body that form no part of the claimed design.

1 Claim, 9 Drawing Sheets
